BED

Jacobus Vincent Fonelli, 5800 16th St. N.W.,
Washington, D.C.

Filed June 20, 1960, Ser. No. 61,025

Term of patent 14 years

(Cl. D5—4)

FIG. 1 is a perspective view of a bed showing my design.

FIG. 2 is a side elevational view.

FIG. 3 is an end elevational view.

The back of the bed is plain and unornamented.

The present application is a continuation-in-part of my application Serial No. D-57,317, filed August 26, 1959, now abandoned.

I claim:

The ornamental design for a bed, as shown and described.
